PERPETUAL CALENDAR

Alexander Hossu, Astoria, N. Y.

Application February 12, 1948, Serial No. 7,841

6 Claims. (Cl. 40—110)

1

This invention relates to a perpetual calendar. More particularly, the invention relates to a photograph mount perpetual calendar which can be ornamented by a photograph which has some especial meaning to the person utilizing the perpetual calendar.

The present invention is directed toward providing a new type of perpetual calendar which will not only be of perpetual value as a calendar but which will also be of perpetual value as a photograph mount to the end that the calendar can be redecorated when desired and kept of ornamental interest as well as of useful interest.

An object of the present invention is to provide a perpetual calendar which is so constructed that it can stand up on a desk or the like and which has a place for a photograph such as a picture of a man's wife or daughter, the photograph being part of the calendar and ornamenting the same.

A further object is to provide a calendar as aforesaid having movable buttons for indicating the day, month and day name, each of the buttons being provided with means for holding it in any position to which it is moved.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a front elevational view of a perpetual calendar constructed in accordance with this invention.

Fig. 2 is an enlarged partial sectional view of the front member only taken on the line 2—2 of Fig. 1.

Fig. 3 is a rear view of one of the parts of the calendar.

Fig. 4 is a diametral section through one of the buttons, taken on the line 4—4 of Fig. 5.

Fig. 5 is a view of one of the pins forming part of the button.

Fig. 6 is a perspective view of the calendar partly open, taken from the hinge side thereof.

Fig. 7 is a section on the line 7—7 of Fig. 6.

The calendar 10, according to the present invention, comprises a front member 11 and a rear member 12, hinged at 13. The rear member 12 consists of a sheet of board 14, such as cardboard, about the inner face edges of which is a frame 15 for retaining a photograph or picture 16. The frame 15 is made of strips of card-

2

board. Each strip is taped at its outer edge by a tape 17. Similarly the outer edges of the board 14 are taped by a tape 18. When the frame 15 is put on the board 14 the two strips 17 and 18 space the frame from the board 14 so that the photograph 16 can be slid into place. A tape 19, covering tapes 17 and 18, binds the frame to the board 14, see Fig. 7. The tape 19 has a slit 20 at the top of the member 12 through which the photograph can be slid. Thus any photograph can be placed in the calendar, making the calendar of interest to the particular person using it. For example, a man can have the calendar on his desk at his place of business and have his child's photograph in it. As the child grows, the photograph can be changed to more recent ones, keeping the calendar up to date as to ornamentation by the photograph.

When the calendar is in use, the members 11 and 12 are superposed and closely engage each other, the hinge 13, which is made of tape, permitting this. The calendar is kept in upright position by a leg 21 which is riveted at its top by rivets 22 to the board 14 and is kept from swinging too far out at its bottom by a tape 23 fastened to the leg and to the board 14.

The member 11 consists, in the main, of an inner plate 24 of transparent plastic, such as Celluloid, and an outer plate of opaque material, such as plastic or cardboard 25, the plates 24 and 25 being united by a peripheral tape 26. Plate 25 has a large central opening 27 in which is disposed an annular ring 28 of smaller outside diameter than the opening 27, leaving an annular track 29. Similarly a ring 30 is disposed in the ring 28, providing a track 31. At its inner edge, at the bottom, ring 30 has a radially inwardly extending portion 32 provided with an arcuate track 33. While plates 24 and 25 are connected by tape 26, ring 28 is held outwardly from plate 24 by a circular rib 34, fastened, as by cementing, to the inner face of ring 28. Rib 34 is a ring of smaller diameter than the large diameter, and of larger diameter than the small diameter of ring 28. Rib 34 is in turn secured to the transparent plate 24.

Since plate 25 is fastened to plate 24 only at its periphery, it can be moved outwardly relative to plate 24 about the edge of the hole or opening 27. Since rib 34 spaces ring 28 outwardly from plate 24, the track 29 forms part of a dove-tail groove, see Fig. 2, formed by the track 29 and the spaces at either side thereof bounded by the plate 24, the plate 25 and the ring 28.

Ring 30 is shown in Fig. 3, looking at its rear face. A ring-shaped rib 35 is cemented about its inner periphery, an arcuate rib 36 is cemented about the inner margin of the portion 32 and filler ribs 37 are cemented between the ribs 35 and 36 at the ends of portion 32. These ribs 35—36—37 are also cemented to plate 24, so that track 31 is similar to track 29, except it is of smaller diameter. Thus ring 28 is mounted between the margin of the opening 27 and the outer edge of the ring 30.

When the rear member 12 is located behind the front member 11, the picture 16 of the rear member can be seen through the ring 30 and the center of the transparent plate 24, as shown in Fig. 1.

Two buttons 38 and 39 are disposed, one in each of the tracks 29 and 31 respectively. A similar button 40 is disposed in track 33. The buttons are best shown in Figs. 4 and 5. This button will be presumed to be button 38, but it will be understood that the three buttons are similar. The button has a laminated head 41 formed of a plurality of layers of cardboard, plastic, or the like, cemented together, seven layers being shown by way of example. The head is raised to provide a knob 42 in its center to provide additional thickness at its center. A tack 43 is associated with the head to form the button, the tack having a base 44, a pin 45 and two opposite cams 46 at the juncture of the base and pin. The cams 46 engage the adjacent lamination of the head. The cams extend the diameter of the pin when it is turned, but the minimum diameter is the diameter of the base of the pin, as is clearly shown in Fig. 5. The pin 45 is held in the laminations of the head partly by being driven therein, and partly by the cement holding the laminations together.

Each button is disposed in its track so that the base 44 is in the dove-tail groove and running along the outer face of the plastic sheet 24, see the button 43 in Fig. 2. The cams and the base of the pin are in the track and the head overrides the adjacent portions on either side of the track. Thus the head of button 38 overlaps plate 25 and ring 28; the head of button 39 overlaps rings 28 and 30; and the head of button 40 overlaps the two portions of portion 32 on opposite sides of track 33.

The operation of the calendar is as follows:

The man using the calendar first opens it up and inserts the photograph or picture of his choice into the frame 15, via the slit 20. He then closes it and stands it up with the frame braced by the leg 21. He then sets the calendar for the current date. Then he moves button 40 to the correct day name. He turns the button slightly so that the cams 46 jam in the track 33 lightly to prevent unauthorized movement of the button 40. He then moves button 39 to the correct month and the button 38 to the correct day and turns each button to actuate the cams 46 thereof.

Each day, button 38 is moved one number and button 40 is moved one space. Each month, button 39 is moved one space. The photograph is visible through the plate 24 and is framed by the inner edges of the ring 30 and portion 32.

While I have illustrated and described the preferred embodiment of my invention, it is to be understood that I do not limit myself to the precise construction herein disclosed and the right is reserved to all changes and modifications com-

ing within the scope of the invention as defined in the appended claims.

Having thus described my invention, what I claim as new, and desire to secure by United States Letters Patent is:

1. A perpetual calendar comprising a transparent plate, a sheet mounted on said plate in spaced relation thereto and formed with a large central opening, a ring set into said opening and secured to said plate in spaced relation thereto, a second ring set into said ring and having a radially inwardly extending portion formed with an arcuate slot forming a short arcuate track, said second ring being secured to said plate in spaced relation thereto, said second ring having an outside diameter less than the inside diameter of said first ring forming between the adjacent edges of said rings an inner circular track, said first ring having an outside diameter less than the diameter of said opening forming between the adjacent edges of said first ring and said sheet an outer track, a circular row of numbers from 1 to 31 imprinted on the edge portions of said sheet and said first ring defining said outer track, a circular row of month names from January to December imprinted on the edge portions of said first and second rings defining said inner track, an arcuate row of day names from Sunday to Saturday imprinted on the edge portions of said second ring defining said short arcuate track, and a button movably disposed in each of said tracks, each of said buttons having a head bearing against the outer faces of the edges of the respective sheet and/or rings defining the respective track, a base spaced from the inner face of said head and disposed in the space between said plate and the respective sheet and/or rings, and a pin integral with said base and extended through the space between the edge portions of the respective sheet and/or rings defining the respective track and secured in said head.

2. A perpetual calendar comprising a transparent plate, a sheet mounted on said plate in spaced relation thereto and formed with a large central opening, a ring set into said opening and secured to said plate in spaced relation thereto, a second ring set into said ring and having a radially inwardly extending portion formed with an arcuate slot forming a short arcuate track, said second ring being secured to said plate in spaced relation thereto, said second ring having an outside diameter less than the inside diameter of said first ring forming between the adjacent edges of said rings an inner circular track, said first ring having an outside diameter less than the diameter of said opening forming between the adjacent edges of said first ring and said sheet an outer track, a circular row of numbers from 1 to 31 imprinted on the edge portions of said sheet and said first ring defining said outer track, a circular row of month names from January to December imprinted on the edge portions of said first and second rings defining said inner track, an arcuate row of day names from Sunday to Saturday imprinted on the edge portions of said second ring defining said short arcuate track, and a button movably disposed in each of said tracks, each of said buttons having a head bearing against the outer faces of the edges of the respective sheet and/or rings defining the respective track, a base spaced from the inner face of said head and disposed in the space between said plate and the respective sheet and/or rings, and a pin integral with said base and extended through the space between the edge portions of the respective sheet and/or rings defining the respective track and secured in said head.

edge portions of the respective sheet and/or rings defining the respective track and secured in said head, said heads being of laminated construction and thicker at their center than at their sides.

3. A perpetual calendar comprising a transparent plate, a sheet mounted on said plate in spaced relation thereto and formed with a large central opening, a ring set into said opening and secured to said plate in spaced relation thereto, a second ring set into said ring and having a radially inwardly extending portion formed with an arcuate slot forming a short arcuate track, said second ring being secured to said plate in spaced relation thereto, said second ring having an outside diameter less than the inside diameter of said first ring forming between the adjacent edges of said rings an inner circular track, said first ring having an outside diameter less than the diameter of said opening forming between the adjacent edges of said first ring and said sheet an outer track, a circular row of numbers from 1 to 31 imprinted on the edge portions of said sheet and said first ring defining said outer track, a circular row of month names from January to December imprinted on the edge portions of said first and second rings defining said inner track, an arcuate row of day names from Sunday to Saturday imprinted on the edge portions of said second ring defining said short arcuate track, and a button movably disposed in each of said tracks, each of said buttons having a head bearing against the outer faces of the edges of the respective sheet and/or rings defining the respective track, a base spaced from the inner face of said head and disposed in the space between said plate and the respective sheet and/or rings, and a pin integral with said base and extended through the space between the edge portions of the respective sheet and/or rings defining the respective track and secured in said head, and cams on the sides of the portions of said pins which extend through the spaces between the edge portions of said sheet and/or said rings defining the respective tracks to engage the respective edge portions when the buttons are turned to retain the buttons against accidental movement.

4. A perpetual calendar comprising a transparent plate, a sheet mounted on said plate in spaced relation thereto and formed with a large central opening, a ring set into said opening and secured to said plate in spaced relation thereto, a second ring set into said ring and having a radially inwardly extending portion formed with an arcuate slot forming a short arcuate track, said second ring being secured to said plate in spaced relation thereto, said second ring having an outside diameter less than the inside diameter of said first ring forming between the adjacent edges of said rings an inner circular track, said first ring having an outside diameter less than the diameter of said opening forming between the adjacent edges of said first ring and said sheet an outer track, a circular row of numbers from 1 to 31 imprinted on the edge portions of said sheet and said first ring defining said outer track, a circular row of month names from January to December imprinted on the edge portions of said first and second rings defining said inner track, an arcuate row of day names from Sunday to Saturday imprinted on the edge portions of said second ring defining said short arcuate track, and a button movably disposed in each of said tracks, each of said buttons having a head bear-

ing against the outer faces of the edges of the respective sheet and/or rings defining the respective track, a base spaced from the inner face of said head and disposed in the space between said plate and the respective sheet and/or rings, and a pin integral with said base and extended through the space between the edge portions of the respective sheet and/or rings defining the respective track and secured in said head, and cams on the sides of the portions of said pins which extend through the spaces between the edge portions of said sheet and/or said rings defining the respective tracks to engage the respective edge portions when the buttons are turned to retain the buttons against accidental movement, said cams being located on diametrically opposite sides of said pins.

5. A perpetual calendar comprising a transparent plate, a sheet mounted on said plate in spaced relation thereto and formed with a large central opening, a ring set into said opening and secured to said plate in spaced relation thereto, a second ring set into said ring and having a radially inwardly extending portion formed with an arcuate slot forming a short arcuate track, said second ring being secured to said plate in spaced relation thereto, said second ring having an outside diameter less than the inside diameter of said first ring forming between the adjacent edges of said rings an inner circular track, said first ring having an outside diameter less than the diameter of said opening forming between the adjacent edges of said first ring and said sheet an outer track, a circular row of numbers from 1 to 31 imprinted on the edge portions of said sheet and said first ring defining said outer track, a circular row of month names from January to December imprinted on the edge portions of said first and second rings defining said inner track, an arcuate row of day names from Sunday to Saturday imprinted on the edge portions of said second ring defining said short arcuate track, and a button movably disposed in each of said tracks, each of said buttons having a head bearing against the outer faces of the edges of the respective sheet and/or rings defining the respective track, a base spaced from the inner face of said head and disposed in the space between said plate and the respective sheet and/or rings, and a pin integral with said base and extended through the space between the edge portions of the respective sheet and/or rings defining the respective track and secured in said head, said sheet being opaque and bound to said plate in spaced relation thereto at its peripheral edges.

6. A perpetual calendar comprising a transparent plate, a sheet mounted on said plate in spaced relation thereto and formed with a large central opening, a ring set into said opening and secured to said plate in spaced relation thereto, a second ring set into said ring and having a radially inwardly extending portion formed with an arcuate slot forming a short arcuate track, said second ring being secured to said plate in spaced relation thereto, said second ring having an outside diameter less than the inside diameter of said first ring forming between the adjacent edges of said rings an inner circular track, said first ring having an outside diameter less than the diameter of said opening forming between the adjacent edges of said first ring and said sheet an outer track, a circular row of numbers from 1 to 31 imprinted on the edge portions of said sheet and said first ring defining said outer track, a circular row of month names from January to December imprinted on the edge portions of said second ring defining said short arcuate track, and a button movably disposed in each of said tracks, each of said buttons having a head bear-

January to December imprinted on the edge portions of said first and second rings defining said inner track, an arcuate row of day names from Sunday to Saturday imprinted on the edge portions of said second ring defining said short arcuate track, and a button movably disposed in each of said tracks, each of said buttons having a head bearing against the outer faces of the edges of the respective sheet and/or rings defining the respective track, a base spaced from the inner face of said head and disposed in the space between said plate and the respective sheet and/or rings, and a pin integral with said base and extended through the space between the edge portions of the respective sheet and/or rings defining the respective track and secured in said head, a rear member behind said plate and having a frame for a picture facing said plate, means pivotally connecting said rear member to said

plate to be movable to a position behind said plate so that a picture contained within said rear member will be visible through the inner periphery of said second ring, and a supporting leg secured to the back face of said rear member.
